UNITED STATES PATENT OFFICE.

WILLIAM E. MURBARGER, OF INDIANAPOLIS, INDIANA.

COMBINED SHAFT-SUPPORT AND THILL-COUPING.

SPECIFICATION forming part of Letters Patent No. 627,939, dated June 27, 1899.

Application filed May 17, 1899. Serial No. 717,200. (No model.)

To all whom it may concern:

Be it known that I, WILLIAM E. MURBARGER, a citizen of the United States, and a resident of Indianapolis, in the county of Marion 5 and State of Indiana, have invented certain new and useful Improvements in a Combined Shaft-Support and Thill-Coupling, of which the following is a specification.

The object of this invention is to provide 10 certain improvements in the combined shaft-support and thill-coupling set forth in my prior patent, dated April 24, 1894, and numbered 518,763, the said improvements being designed to add materially to the effectiveness and durability of the device.

The present invention therefore contemplates certain improvements in the details of construction of the parts constituting the device shown in the aforesaid patent, relating 20 particularly to the locking-plate for the pivot-bolt and means for holding said locking-plate in place; also, to the tension-plate carrying the spring shaft-support and to the means of connecting the flanged presser-roller to the 25 spring.

The following specification enters into a detail description of the application of the improvements and their practical advantages, reference being had to the accompanying 30 drawings and to letters thereon, which designate the different parts, and what I desire to protect by Letters Patent is more specifically set forth in the appended claims.

In the drawings which form a part of this 35 specification, Figure 1 is a perspective view of the improved shaft-support and thill-coupling. Fig. 2 is a front elevation of the shaft-supporting spring and its roller. Fig. 3 is a detail perspective view of the tension-plate 40 and locking-plate carried thereby. Fig. 4 is a side view of the tension-plate.

Referring to said drawings, A designates the axle-clip, which is provided with the usual apertured ears a a, between which the eye b 45 of the thill-iron B is placed and pivotally supported by a bolt or pin C.

D designates the tension-plate, which is provided with the curved neck d, adapted to fit against the rear portion of the eye of the thill-iron, and also with the opposite shoulders d' d', 50 which will contact with the ears a and prevent an upward movement of the tension-

plate. The outer side of the depending portion or body of this tension-plate is provided at one side, near the edge, with a series of 55 apertures or holes d², and as these holes tend to weaken the plate I reinforce the same on the rear side by a semi-annular boss d³, as shown in Fig. 4. The said plate is also provided with an annular boss or integral ring d⁴ on its outer side, the series of holes hereinbefore referred to extending partly around said boss or ring. The coiled portion e of the spring shaft-support E is adapted to fit over or encircle the annular boss, and the bent end 60 e' of the coil is passed into engagement with any one of the series of holes d². Instead of providing the spring shaft-support with a double bend, as shown and described in my prior patent referred to, the said spring or 65 arm of the same is gradually curved, as shown in the accompanying drawings, giving a neater appearance to the device. By so curving the arm the bent outer end e² will be brought in proper position with respect to the shaft and 70 the flanged roller F, which is journaled on the said bent end, will engage the shaft. This 75 roller is held upon the bent end of the spring by threading the terminal of the latter and screwing a washer thereon, the washer being of sufficient thickness to permit it to receive a threaded aperture, it being understood, of course, that the threads on the spring terminate so that the washer will not be brought against the flanged roller to jam it 80 against the arm of the spring, said roller serving principally as an antifriction device, while the flanges or heads insure a positive engagement of the shaft-support with the shaft. The 85 tension of the spring shaft-support can be increased or diminished by turning the coiled portion, the adjustment being held by engaging the bent end e' with one of the apertures or holes d² in the tension-plate, and the annular boss on said tension-plate will properly 90 support the coil and increase the efficiency of the spring.

To provide for positively supporting the locking-plate G in engagement with the pivot-bolt of the thill-coupling, a lug h is formed on 100 the arm of the tension-plate, said lug being so positioned as to support the end of the plate opposite that through which the retaining-screw i passes. In my prior patent referred

to the said plate was supported only by the screw and nut, and when a single bolt-retaining flange *g* was provided the locking-plate was liable to drop down out of engagement 5 should the nut become loose. Thus the application of the supporting-lug to the tension-plate, which carries the locking-plate, will more securely hold said locking-plate in place.

The improvements herein shown and described have suggested themselves after many practical applications of my combined shaft-support and thill-coupling, and in order to more fully protect my invention

What I desire to secure by Letters Patent is—

1. A combined shaft-support and thill-coupling, comprising the tension-plate having the curved bearing-neck and formed with the annular boss and series of perforations extending partly around said boss, the spring shaft-support having a coiled portion encircling the annular boss and a bent end adapted to engage the perforations, the arm of the spring being curved and carrying a roller at its outer end which contacts with the under side of the shaft, substantially as shown and for the purpose set forth.

2. A combined shaft-support and thill-coupling, comprising the tension-plate having the curved bearing-neck and formed with the annular boss, series of perforations extending partly around said boss, and reinforcing-boss at the rear side of the plate; the spring shaft-support having a coiled portion encircling the annular boss and a bent end adapted to en-

gage the perforations, the arm of the spring being gradually curved laterally and carrying a roller at its outer end which contacts with the under side of the shaft, substantially as shown and for the purpose set forth.

3. A combined shaft-support and thill-coupling, comprising the tension-plate provided with the curved neck, annular boss, series of adjusting-apertures and reinforcing-boss; the spring shaft-support having the coiled portion 45 encircling the annular boss and bent end adapted to engage the perforations, the arm of the spring being curved laterally and provided at its outer end with a bend forming a pintle having a threaded extremity; together 50 with the flanged roller mounted on the pintle, and the threaded washer engaging the threaded end of said pintle, substantially as shown and for the purpose set forth.

4. The combination with the tension-plate, 55 arranged as set forth, of the locking-plate secured thereto immediately below the coupling-joint by a screw passing through a slot in said plate, the locking-plate having a bolt-retaining flange; together with the lug formed 60 on the tension-plate below one end of the locking-plate, substantially as shown and for the purpose set forth.

In testimony whereof I affix my signature in the presence of two witnesses.

WILLIAM E. MURBARGER.
